George Blod

UNITED STATES PATENT OFFICE.

MAX KOSSMANN, OF BROOKLYN, NEW YORK

LAMP-SHADE HOLDER.

1,216,818.

Specification of Letters Patent. Patented Feb. 20, 1917.

Application filed September 18, 1916. Serial No. 120,679.

To all whom it may concern:

Be it known that I, MAX KOSSMANN, a citizen of the United States of America, residing at Brooklyn, Kings county, and State 5 of New York, have invented certain new and useful Improvements in Lamp-Shade Holders, of which the following is a full, clear, and exact description.

This invention relates to improvements 10 in shade holders or brackets, one of the objects of the invention being to provide a holder or bracket arranged to engage or grip the socketed terminal of an electric light circuit, or in other words, an electric lamp socket, the shade which is supported by the bracket acting to prevent the withdrawal of the holder or bracket from the socket.

A further object of my invention is to 20 provide a shade holder or bracket arranged not only to support a shade, but also to support a shield to be used in connection with lamps of high candle power or brilliancy, such for instance as nitro-lamps or bulbs.

25 A further object of my invention is to provide a shade holder which can be caused to engage a lamp socket without the use of screws or threaded connections, thereby not only reducing the cost of manufacture, but 30 permitting more ready attachment.

I will now proceed to describe my invention in detail, the essential features of which will be summarized in the appended claims, 35 reference being had to the accompanying drawing, forming part hereof; wherein—

Figure 1 is a face view of an ordinary electric lamp socket having my improved shade holder attached thereto, a portion of a shade being shown in section;

40 Fig. 2 is a top plan view of the upper or clamping end of the bracket;

Fig. 3 is a side view thereof;

Fig. 4 is a side elevation of the assembled socket, shade and shield; and

45 Fig. 5 is a side elevation, partly in section, showing a modified form of my invention.

As herein embodied my invention comprises a frame 6 consisting of a cylindrical portion 7 having an inwardly directed flange 8 provided with an aperture 9, and an outwardly extending angularly disposed flange or shade-support 10. To the shade-support or flange 10, I secure a plurality of fingers 11 (in this instance three) which are yieldable and constitute a clamp for holding said bracket to said socket, besides other functions herein stated. As can be seen, the fingers 11 are secured to the inner surface of the flange 10 intermediate their ends, that portion of the fingers, above the point of securing, projecting through openings formed in the cylindrical wall 7 and flange 8 of the frame 6 (see Fig. 3). The upper end of each finger is turned inwardly as at 13 to form rounded projections. The 65 clamping portion of each finger, indicated by 14, is free to be moved toward or away from the center of the frame 6 within the openings or slots 15 in said frame 6. The lower member of each finger 11 is provided 70 with a hook or supporting element 16 to support a shield 17 which can be used in combination with the shade 18, if desirable. The function of the flange or support 10 is to retain the shade 18, as shown in Fig. 1, 75 as said shade will rest upon said support. To attach the device, the frame 6 will be applied from below the socket 19, after the shade has been slipped over the socket, the lower end of said socket passing through the 80 aperture 9 in said frame, the flange 8 being pressed up against the beading 20 on the socket. During the application of the device, as above set forth, the clamping portion 14 of each finger 11 will be sprung outwardly to pass over the beading 20, and when finally positioned, the beading 20 will be located between the flange 8 and rounded 85 projections 13 on the fingers 11, as shown in Fig. 1. When the shade 18 is allowed to rest 90 upon the flange or support 10, the neck 21 thereof will act to prevent the clamping portions 14 of the fingers from springing outwardly or away from the beading 20. Therefore the shade acts as a locking element 95 for the clamping elements 14. The outside diameter of the cylindrical portion 7 of the frame is but slightly less than the inside diameter of the neck 21, hence when the shade is allowed to rest upon the flange 100 or support 10, the clamping elements 14 will be in contact both with the shade and socket 19, or at least in such close relationship as to prevent the clamping elements from moving outwardly sufficiently to permit the 105 rounded ends or projections 13 from being slipped over the beading 20 should an abnormal downward pressure be applied to the shade. In some instances I may secure to the lower end 16 of each finger a metallic 110 shield 22, and employ a globe 23 which will be supported by the supporting elements, or

ends 16 of the said fingers. By this means, I am able to completely incase an electric light bulb, which might be desirable where lamps of high power are used.

5. What I claim as my invention is:

1. In combination with a lamp shade and a shade holder provided with a central aperture, a yieldable clamp carried by said holder and a lamp socket provided with an 10 annular bead and adapted to enter said opening and be engaged by said clamp catching over said bead, the shade being supported by said holder and the neck of the shade preventing by contact with the 15 clamp the outward yielding of the latter and the consequent disengagement of said clamp and holder from the socket.

2. A shade holder comprising a cylindrical vertical body having openings in its 20 vertical wall, in combination with a clamp connected to said holder and having yielding clamping elements, located in said openings which elements engage the lamp socket in their innermost position and are arranged to work through said holder, and a shade adapted to prevent, by its contact with the said clamping elements, the outward movement of the latter through the holder for disengagement from said socket.

30. 3. A shade holder comprising a hollow cylindrical vertical body portion, an in-turned flange carried thereby at one end thereof and provided with a central aperture, an outwardly directed angularly disposed flange carried by said cylindrical portion at the opposite end thereof, arranged to support a shade, said body portion and inturned flange being provided with a plurality of communicating slots, and a yieldable clamping element located in each slot 40 and movable inward and outward through said slot and means for preventing the outward movement of said elements to disen-

gage the said holder from said socket while the shade is in position for use.

45

4. A shade holder comprising a plurality of yieldable fingers, the upper end of each finger being turned inwardly to form projections, the lower end of each finger being provided with a retaining means for a depending shield distinct from the shade, and a frame secured to said fingers intermediate their ends.

50

5. In combination with a shade having a cylindrical hollow neck, a holder therefor 55 consisting of a frame arranged to loosely fit within said neck, means carried by the frame to support said shade, a plurality of yieldable clamping elements carried by said frame and arranged to engage a lamp socket, the neck of said shade being adapted by external contact with said clamping elements to maintain said clamping elements in contact with the lamp socket when said shade rests upon the supports therefor.

65

6. A shade holder comprising a hollow cylindrical body portion, an inturned flange carried thereby at one end thereof and provided with a central aperture, an inturned upper flange and a downwardly flaring 70 flange carried by the lower end of said cylindrical portion, for supporting a shade, said body portion and upper flange being provided with a series of communicating slots, in combination with a series of elastic 75 parts attached to said shade holder and having depending globe supporting parts and upper resilient parts working through said slots.

Signed at New York city, N. Y., this 15th 80 day of September, 1916.

MAX KOSSMANN.
